GOLF CLUB GRIP

Francis T. Brewer, Hinsdale, Ill., assignor, by mesne assignments, to Wilson Sporting Goods Co., River Grove, Ill., a corporation of Delaware

Filed Apr. 26, 1966, Ser. No. 2,029

Term of patent 14 years

(Cl. D34—5)

FIG. 1 is a front elevational view of a golf club grip embodying my new design;

FIG. 2 is a fragmentary view of an upper end portion thereof drawn to a larger scale than FIG. 1 and viewed from a side opposite thereto;

FIG. 3 is a fragmentary side sectional view of the grip taken substantially as indicated by a line 3—3 and accompanying arrows in FIG. 2; and

FIG. 4 is an end sectional view taken substantially as indicated by a line 4—4 and accompanying arrows in FIG. 1.

The broken line illustration of a shaft and club head is for illustrative purposes only.

The characteristic feature of my design resides in the combination on the golf club grip disclosed of the incised chevron pattern arranged generally in vertical rows, each row comprising spaced apart groups of five chevrons, and each group being offset from the adjacent rows, so as to present a spiral effect, all as shown.

I claim:

The ornamental design for a golf club grip, substantially as shown and described.
